UNITED STATES PATENT OFFICE.

LUCIUS CARRIER, OF EAST DOUGLAS, MASSACHUSETTS.

KNIFE-HANDLE.

Specification of Letters Patent No. 27,349, dated March 6, 1860.

To all whom it may concern:

Be it known that I, LUCIUS CARRIER, of East Douglas, in the county of Worcester and State of Massachusetts, have invented 5 a new and useful Improvement in the Construction of Knife-Handles; and I do hereby declare that the following is a full, clear, and exact description of the same, reference being had to the annexed drawings, making 10 a part of this specification, in which—

Figure 1, is a side view of a handle constructed according to my invention, Fig. 2, a transverse section of the same; Fig. 3, a back view of the same.

15 Similar letters of reference indicate corresponding parts in the several figures.

This invention although applicable to handles for all kinds of cutlery is more especially designed for large knives, such as the 20 Spanish knife or machete and the like.

The invention consists in having the body of the handle formed of pieces of horn, leather or wood and covering the same with a single piece of horn secured in proper position by rivets or bolts substantially as 25 hereinafter described.

To enable those skilled in the art to fully understand and construct my invention I will proceed to describe it.

30 A, represents a portion of the blade of a knife and a a b b represent strips of horn which are placed, two at each side of the tang c of the blade A, as shown clearly in Fig. 2. The strips of horn a a b b extend 35 the whole length of the handle, and they are covered by a piece of horn d, which is bent around said pieces and is secured thereto by bolts e a necessary number of which pass through the tang c and not only secure 40 the cover d to the body or filling of the handle, but, also secure the handle to the tang.

The cover d extends around the back of the body or filling, and it ends nearly or quite meet in front. The handle therefore 45 has a smooth exterior, is very firm and durable and may be manufactured economically.

The body or filling may be of pieces of horn as described, or raw hide, or leather may be used, and also wood. Various materials might be employed for this purpose as 50 the cover d, is what gives the character to the handle and constitutes its essential feature.

The horn that forms the cover, is cut out in proper shape and in order to enable it to 55 be bent properly it is boiled, and, heated in the usual or in any proper way so as to render it soft and pliant. The body or filling may be of any size according to the size of the handle required.

60 Knife handles have been made of strips of horn, placed one over the other at each side of the tang, and secured longitudinally thereto by bolts, but, so far as I am aware a cover of horn has never been employed to 65 extend nearly or quite around the handle, to form a smooth handle equal to one formed of a solid substance throughout. The handles constructed entirely of horn strips are liable to become rough in consequence of 70 the edges of the strips turning or curling, under the influence of the heat of the hand, an effect peculiar to horn. By my invention this difficulty is obviated and a perfectly smooth and durable handle obtained equal to 75 one formed of a solid substance throughout.

I do not claim a knife handle formed of strips of horn, connected together and to the tang of the knife by bolts, for such handles have been previously constructed, but: 80

I do claim as new and desire to secure by Letters Patent, as an improved article of manufacture—

A knife handle formed of a body or filling of horn, wood, or other suitable material 85 covered by a single piece of horn substantially as described.

LUCIUS CARRIER.
